RAILWAY TRUCK

Harry M. Pflager, St. Louis, Mo., assignor to General Steel Castings Corporation, Granite City, Ill., a corporation of Delaware

Application April 20, 1935, Serial No. 17,415

14 Claims. (Cl. 105—190)

This invention relates to trucks for railway rolling stock and particularly to trucks for light weight cars intended for high speed trains.

Trucks intended for passenger car service have heretofore generally embodied bolsters carried by means of leaf springs supported by hangers swinging directly from the truck framing, which framing is yieldingly supported by means of coil springs either placed on top of the journal boxes or on equalizers extending from one journal box to the other.

Trains are now being built which are of lighter body construction and intended for travel at higher speeds than customary heretofore. The relative light weight of the body compared with the weight of the trucks, including wheels and axles, to which must be added in many cases the weight of the motors, gives a much different ratio between the weight of the car body and the weight of the trucks than in the ordinary car used in the past, and this introduces new operating conditions which require a truck adapted to meet these new conditions.

The object of the present invention is to construct a truck for light weight cars that will produce the best riding qualities at high speeds. This is accomplished by providing yielding elements between the journal boxes and truck frame or between the equalizers and the truck frame, to absorb as far as possible the primary shocks from the track to the truck frame, and providing in addition a secondary set of yielding elements of different characteristics, mounted in the truck frame. Swing hangers are suspended from these secondary yielding elements, and other yielding elements are supported by the swing hangers, and the truck bolster, which carries the load of the car, is carried by the latter yielding elements. This arrangement provides a very simple mounting of the swing hanger on the truck frame but gives the hanger a floating movement in addition to its usual pivotal movement.

The secondary set of yielding elements, which, for the purpose of this description, are called the floating hanger springs or yielding elements, receive the shocks and vibrations that are transmitted by the truck frame and reduce them before the shocks pass into the swing hangers and through the yielding elements carried by the hangers, which latter elements absorb further portions of the shocks which have passed through the first two mentioned sets of yielding elements.

These floating hanger yielding elements, in addition to absorbing the vertical shocks trans-

mitted from the track, also absorb some of the lighter lateral thrusts, especially those thrusts due to the irregularity of the track and the rail joints, thus causing the truck frame to jiggle from side to side as the forward wheels of the truck reach first one irregularity in the track and then another.

With the construction heretofore used, the swing hangers are inclined from the vertical to create initial resistance to lateral movement; and the forces due to the jiggling of the truck frame on straight track are transmitted to the body of the car as they are not of sufficient magnitude to cause the inclined swing hangers to overcome initial resistance, while in this invention such forces will be absorbed in the natural lateral flexibility of the floating hanger yielding elements which have a limited side motion. When the car travels at high speed and strikes a curved section of the track, the swing hangers then come into operation offering increasing resistance to the side motion of the car and absorbing the lateral thrusts of the car body.

The yielding elements supporting the swing hangers add a new and improved feature to the truck construction, as they not only absorb and reduce the vertical shocks delivered to the car body by the track, but act also to steady the car body on straight track and help the swing hangers absorb severe lateral shocks when rounding curves, thus producing smooth and easy riding of the car.

The lighter the weight of the car body, as compared with the truck, the greater is the tendency to transmit the forces, set up by the jiggling of the truck, to the car body and cause unpleasant vibrations. This tendency is overcome in my invention by the use of the floating hanger yielding elements which support the inclined swing hangers.

A further object of this invention is to provide a truck with cross transoms so arranged that the floating hanger yielding elements can be placed in them in the same general transverse plane occupied by the swing hangers, thus economizing in the length of the wheelbase of the truck and simplifying the construction thereof.

These objects and others are attained by the structures illustrated in the accompanying drawings, in which—

Figure 1 is a top view of a truck embodying the invention.

Figure 2 is a vertical longitudinal section taken on the line 2—2 of Figure 1.

Figures 3 and 4 are vertical transverse sec-

tions taken on the corresponding section lines of Figure 1.

Figures 5, 6, and 7 are detail views corresponding, respectively, to Figures 1, 2, and 4 but showing a modification.

The truck illustrated in Figures 1 to 4 includes a pair of axles 1 having journals and journal boxes 2. Resting on each journal box 2 are yokes 3 having end portions 4 terminating a short distance longitudinally in each direction from the box. Secured to the portions 4 of the yokes are spring seats 5, carrying coiled springs 6 engaging spring cap structures 7 formed on the under-surfaces of the truck side frame members or wheel pieces generally indicated at 8.

The wheel pieces 8 include pedestals 9 slidably receiving the journal boxes 2, and the wheel pieces on opposite sides of the truck are rigidly tied together by means of transom structures generally indicated at 10. Each transom structure includes spaced elements 19 and a transverse bottom web 11 having spring seats 12 adjacent each wheel piece. Resting on the seats 12 are coiled springs 13 supporting transverse members 14 extending between the springs on opposite sides of the truck to maintain the centers of the springs at an equal distance from each other. At each end of each member 14 is the flattened spring cap portion 15 having a concave bearing 16 pivotally mounting the cross bar of an inverted U-shaped floating hanger 18. The legs of hangers 18 depend through slots 20 in the transom bottom member 11.

The hangers 18 have slots 21 in the lower portions of their legs, receiving the end portions of bars 22. The middle portions of bars 22 engage the ends 23 of the spring plank 24 which carries the elliptic springs 25 mounting the main bolster 28 in the usual manner, the spring bands 26 being seated between the lugs 27 on the spring plank and the lugs 28 on the bolster. Bolster 28 has the usual side bearing mountings 30 and center bearing portion 31 for cooperating with the body side and center bearings (not shown).

Wear plates 32 are provided on adjacent surfaces of the bolster and transoms.

Figures 5, 6 and 7 illustrate a modification in which the transom 40 and transverse member 34 have laterally spaced recesses for the coil springs 41, and the floating swing hanger 33 is a single link located intermediate springs 41 and extending through slots 35 and 36 in members 34 and 40, respectively. The link is suspended by a pin 39 bridging the slot 35 in the spring cap and the link carries the spring plank cross bar 38 in the usual manner.

This structure operates substantially the same as the form illustrated in Figures 1 to 4 which functions as follows: the truck load is transmitted from the bolster 28 to the journal boxes through the three sets of springs 25, 13 and 6. When the vehicle enters a curved section of the track, or is submitted to other lateral forces, the transverse members 14 move slightly laterally due to the lateral yielding of springs 13. This lateral movement is limited by contact between the extremity of the members 14 and the wall 37 on the wheel pieces. After this lateral movement of members 14, the bolster and spring plank swing laterally with hangers 18 and this movement absorbs the balance of the shock due to the rising arc of the hangers.

The slight lateral shocks produced by track irregularities on straight track are delivered to the truck frame and absorbed by the lateral

yielding of springs 13 and thus are not carried into the car body, and such absorption is not dependent upon overcoming resistance intentionally provided by swing hangers.

The improved truck has a super-spring arrangement which produces easier riding qualities than the usual passenger truck and is arranged to dissipate severe lateral as well as vertical shocks. Due to the different characteristics of the various springs, each has a dampening effect upon the others, and this effect, together with the other results obtained, produces a smooth and easing riding truck.

Although the forms of the invention described above and illustrated include transverse members with a spring cap at each end riding on the coiled springs and rigidly spacing the upper ends of opposite hangers from each other, it is noted that the caps for the floating hangers may be disconnected or free of each other, thus increasing the independent action of opposite hangers.

The invention is not limited to the combination of coil and elliptic springs as referred to in the detail description, but any arrangement of yielding supports may be embodied in the invention including such modifications as pneumatic springs, or springs in the form of rubber blocks, or combinations of such springs with the more familiar coil and elliptic springs illustrated, and other details of the structure described may be modified in various respects without departing from the spirit of the invention, and the exclusive use of all such modifications coming within the scope of the claims is contemplated.

I claim:

1. In a railway truck, wheels, axles, journal boxes, a truck frame, springs supporting said truck frame from said journal boxes, members directly mounted on said truck frame constructed and arranged to yield vertically and horizontally, swing hangers supported by said members, a spring plank carried by said swing hangers, springs supported by said spring plank, and a bolster supported by said latter springs.

2. In a railway truck, a truck frame including spaced cross transoms, springs supported directly by said transoms and constructed and arranged to yield vertically and horizontally, spring caps mounted on said springs, swing hangers carried by said spring caps, a spring plank carried by said swing hangers, and a bolster yieldably mounted on said spring plank.

3. Structure as specified in claim 2 in which the springs are mounted in recesses in said transoms.

4. In a railway truck, a truck frame including spaced cross transoms, springs supported directly by said transoms, spring caps mounted on said springs, swing hangers carried by said spring caps, a spring plank carried by said swing hangers, and a bolster yieldably mounted on said spring plank, said spring caps being connected by transverse members extending parallel to said transoms.

5. In a railway truck, wheels and axles, a frame yieldingly carried thereby, springs seated on said frame, spaced transverse members mounted directly on said springs, swing hangers suspended from said members, and a bolster spring supported from said hangers, said first-mentioned springs yielding horizontally and vertically relative to said frame to provide corresponding movements of said members and the swing hangers and bolsters supported thereby independently of movement of said frame.

6. In a railway truck, frame members each having spaced spring seats, coiled springs on said seats, transverse members carried by said springs, hangers pivoted directly on said transverse members and being bodily movable with said members horizontally and vertically as well as being movable about their pivots on said members, leaf springs carried by said hangers, and a bolster carried on said leaf springs. 5
- 5 7. In a railway truck, wheel pieces, spaced transom structures rigidly connecting said wheel pieces, springs mounted directly on said structures, transverse members floating on said springs, swing hangers carried by said transverse members, and a bolster carried by said hangers. 10
- 10 8. The combination of elements specified in claim 7 in which said transom structures include parts at both sides of said transverse members for resisting movement thereof longitudinally of the truck, said hangers depending through apertures in said structures. 15
- 15 9. In a railway truck, wheel pieces, longitudinally spaced members projecting inwardly therefrom, springs carried by said members, hangers pivotally supported on said springs, each of said hangers depending through the associated projecting member, and a bolster yieldingly carried by said hangers, the hanger mounting portions of said springs being movable horizontally and vertically under the thrusts of forces transmitted between said bolster and said wheel pieces. 20
- 20 10. In a railway truck, a truck frame, springs mounted directly on said truck frame, swing hangers mounted on said springs and having floating horizontal yielding due to movement of the upper portions of said springs free of contact with said frame, and a bolster carried by said hangers. 25
- 25 11. In a railway truck, wheels and axles, a frame mounted thereon and having stationary seats at opposite sides of the truck, springs mounted on said seats, a member extending from one of said springs to the other and carried thereby, and movable transversely of the truck 30
- 30 12. In a railway truck, a rigid frame, springs seated directly on said frame at the sides of the truck, a rigid member mounted on said springs and connecting a spring at one side of the truck with a spring at the other side of the truck, the member mounting portions of said springs being yieldable horizontally of the truck with movement of said member independently of any vertical movement of said springs, devices carried independently of each other by said member at opposite sides of the truck and movable laterally of the truck on said member, and a bolster carried by said devices and movable therewith laterally of the truck relative to said member. 35
- 35 13. In a railway truck, wheels and axles, a main frame carried on said wheels and axles, springs seated on said frame, spaced transverse members mounted directly on said springs, swing hangers suspended from said members, and a bolster carried on said hangers, said springs yielding horizontally and vertically independently of said frame to produce corresponding movement of said members independently of the movement of said frame, wheels and axles. 40
- 40 14. In a railway truck, wheels and axles, a rigid frame mounted thereon, coiled springs with their axes disposed vertically and having their lower portions seated at longitudinally spaced points on said frame, members mounted on the upper portions of said springs, swing hangers pivotally carried directly by said members, and a bolster carried by said hangers, the member supporting portions of said springs being laterally yielding and free of restraint by said frame permitting lateral movement of said members to absorb lateral forces set up by the transverse jiggling of the truck frame insufficient to move said hangers on their pivots and thereby prevent such forces being transmitted to the vehicle body. 45
